UNITED STATES PATENT OFFICE.

COLUMBUS D. ZELLNER, OF DELTA, OHIO.

NECK-YOKE.

SPECIFICATION forming part of Letters Patent No. 292,886, dated February 5, 1884.

Application filed October 23, 1883. (No model.)

To all whom it may concern:

Be it known that I, COLUMBUS D. ZELLNER, a citizen of the United States, residing at Delta, in the county of Fulton and State of Ohio, have 5 invented a new and useful Neck-Yoke, of which the following is a specification, reference being had to the accompanying drawings.

This invention relates to neck-yokes for vehicles; and it has for its object to provide a 10 device which shall possess superior advantages in point of simplicity, durability, and general efficiency, and in which special provision shall be made for renewing the leather or packing in the neck-yoke ring when worn out, thus enabling the said ring to last longer and be more serviceable than those of ordinary construction.

To this end my invention consists in the improved construction and arrangement of parts, 20 which will be hereinafter fully described, and particularly pointed out in the claims.

In the drawings hereto annexed, Figure 1 is a perspective view of a neck-yoke embodying my improvements. Fig. 2 is a vertical 25 sectional view taken through the neck-yoke ring. Fig. 3 is a detail showing in perspective the several parts of the invention detached from each other.

The same letters refer to the same parts in 30 all the figures.

A in the drawings designates the neck-yoke, and B the ring, which is in practice attached to the yoke, and which passes over the front end of the tongue. The body of the said ring 35 may be constructed of malleable metal or other suitable material, and is provided with a flange or band, C, fitting around the neck-yoke, and secured to the latter by means of screws or bolts D D, which should be square-headed, so as to be readily adjustable and detachable by means of an ordinary wrench.

The ring or plate, which is designated by letter E, is provided on its front and rear sides with annular flanges F F, as clearly 40 shown in the drawings.

Seated in the opening H of the ring or plate E is a ring, I, of leather, which is provided with flanges J J, fitting within the annular flanges F of the said plate, as shown.

The ring I, with its flanges, is constructed 50 in any suitable manner and connected by stitching or otherwise, as at L, and may be conveniently inserted and secured in place by means of bolts M, as shown in the drawings.

The operation and advantages of this invention will be readily understood from the foregoing description, taken in connection with the drawings hereto annexed. When the leather of the yoke-ring wears out, it may be easily detached and a new leather inserted, thus rendering the device again as useful as a new one. The reinserting of leather may be repeated as often as desired, the leather portion of the ring 60 being the only one which is exposed to wear.

I claim as my invention and desire to secure 65 by Letters Patent of the United States—

1. In a neck-yoke ring, the combination, with a body-plate made of metal and having annular flanges on its front and rear sides, of a leather packing-ring seated in an opening 70 in the said body-plate, and having flanges fitting within the flanges of the latter, as set forth.

2. In a neck-yoke ring, the combination of a metallic body-plate having a securing flange or band, and provided with an opening 75 rounded by annular flanges on its front and rear sides, a packing-ring seated in the said opening, and having flanges fitting within the flanges of the body-plate, and transverse fastening bolts or rivets, as set forth.

In testimony that I claim the foregoing as my own I have hereto affixed my signature in presence of two witnesses.

COLUMBUS D. ZELLNER.
